UNITED STATES PATENT OFFICE

157,646

PANTIES

Amy S. Vaden, Petersburg, Va.

Application November 26, 1947, Serial No. 142,817

Term of patent 14 years

(Cl. D3—17)

To all whom it may concern:

Be it known that I, Amy S. Vaden, a citizen of the United States, residing at Colonial Heights, Petersburg, county of Chesterfield, State of Virginia, have invented a new, original, and ornamental Design for Panties, of which the following is a specification, reference being had to the accompanying drawing, forming a part thereof.

The figure is a front view of a panty showing my new design. The back of the panty is identical with the front.

I claim:

The ornamental design for panties, substantially as shown and described.

AMY S. VADEN.
